E. BERLINER.
Photophonic Transmitter.

No. 235,120.

Patented Dec. 7, 1880.

Reference is made to patent No. 235,120, and to the accompanying specification, and it is desired to describe the invention as follows: A vertical wall or partition, B , is provided with a slot, C , through which a vertical rod, D , passes. The rod, D , is provided with a curved surface, E , which is in contact with the wall, B , and the rod, D , is connected to a suitable recording device.

Inventor:

Emile Berliner

UNITED STATES PATENT OFFICE.

EMILE BERLINER, OF BOSTON, MASSACHUSETTS.

PHOTOPHONIC TRANSMITTER.

SPECIFICATION forming part of Letters Patent No. 235,120, dated December 7, 1880.

Application filed September 3, 1880. (No model.)

To all whom it may concern:

Be it known that I, EMILE BERLINER, of Boston, Massachusetts, have invented a new and useful Photophonic Transmitter, of which the following is a specification.

This improvement relates to that kind of instruments called "photophones," in which a beam of light is set into vibration by being reflected from a vibratory reflector, or in which the amount of light transmitted at each sound-vibration is regulated by the movement of a diaphragm or other vibratory medium.

In my improvement I make use of a heat-flame of low luminous quality—as, for instance, the flame of a Bunsen burner, or of an oxyhydrogen light, which is hardly visible, but which may heat other substances brought into its reach to incandescence, so that they become luminous, and to an extent as they are brought into contact with the flame, and I arrange a pencil of platinum, calcium, asbestos, or similar refractory substance so that its point is just in contact with the said flame, and I vibrate this pencil by means of a diaphragm, to which it is secured, or by which it may be acted upon. By this means I bring more or less of the pencil in contact with the flame, and the light emitted by the pencil will therefore in strength be proportionate to the amplitude of each vibration, and light-waves, varying in intensity and number in proportion to the transmitted sound-waves and their intensity, will result from this manipulation.

In the drawings, A is a heat-flame of low luminous quality—as, for instance, a Bunsen flame or an oxyhydrogen light. B is a pencil of platinum, calcium, asbestos, or similar refractory substance, with its point just in contact with the flame. The pencil is attached to the center of a diaphragm, C, suitably mounted and provided with a mouth-piece like the mouth-piece of an ordinary Bell telephone, and this diaphragm may or may not be provided with a damper, D.

By uttering now or producing sound in the neighborhood of the diaphragm the same will vibrate, and the pencil B will be brought in more or less contact with the flame and will give out a light of varying brilliancy, each vibration in accordance with the amplitude of the transmitted sound-wave.

I do not broadly claim the art of transmitting undulatory light-waves corresponding to the undulatory waves of sound and articulate speech; but

What I do claim is—

A photophonic transmitter consisting of a heat-flame of low luminous quality, A, a pencil, B, of refractory substance in contact with the flame, and diaphragm C, substantially as and for the purpose set forth.

EMILE BERLINER.
